UNITED STATES PATENT OFFICE.

JOHN B. SHEPPARD, OF NEW YORK, N. Y.

MECHANICAL TOY.

1,168,829.

Specification of Letters Patent. Patented Jan. 18, 1916.

Application filed November 16, 1914. Serial No. 872,472.

To all whom it may concern:

Be it known that I, JOHN B. SHEPPARD, of the city of New York, county and State of New York, have invented certain new and useful Improvements in Mechanical Toys, of which the following is a full, clear, and exact description, reference being had to the accompanying drawing, forming part of this specification.

10 My invention relates to means for producing a toy representation of a pitcher and batsman in the acts respectively of pitching and batting a miniature baseball.

My invention consists in the combination 15 on a plane representing a baseball field, of two small figures, one representing the player in a game of baseball known as the pitcher, and the other representing the player known as the batsman or batter, 20 with the figure representing the pitcher so devised and operated that upon the application of a certain and suitable motive power, a small ball representing a baseball will be thrown, pitched or projected from 25 the hand of said figure toward the figure representing the batsman, and the figure representing the batsman so devised and operated that upon the application of the same certain and suitable motive power, the 30 said figure together with his bat will so move that the bat will strike the small ball thrown, pitched or projected from the figure representing the pitcher, with sufficient 35 force to knock the said small ball a considerable distance. And my invention comprises the further features hereinafter described and more at length recited in the claims.

It must be understood that the drawing 40 does not represent the toy in its true or relative proportions, but that in the actual toy, the figures representing the pitcher and batsman would be farther apart than is shown, and the various parts of the operating device would be spaced and arranged in positions fixed by the locations of the said figures.

In the drawing, Figure 1 represents an 45 elevation of a toy containing my invention, the front of the standard or platform of the same being removed to more fully disclose the features of the operating mechanism. Fig. 2 represents a plan of the same with the top of the platform cut away to more 50 fully disclose the features of the operating mechanism.

In Fig. 1, *a* is the figure representing the pitcher and *b* is the figure representing the batsman. The right hand *c* of the pitcher is made with a recess or hollow *d*, of sufficient size and shaped so as to receive and hold, while the figure *a* is at rest, a small bell *e* representing a baseball. The figure *b* is made holding a bat *f* in the conventional attitude of a batsman about to strike at a pitched ball. The figure *a* has the right arm *R* attached to it by a tight pin *T*, so that the arm may be adjusted vertically to project the ball at the proper elevation to meet the bat *f* of the figure *b*. The figures *a* and *b* are mounted firmly upon posts *g*, *g'* which posts extend and move freely through the top or platform *h* (Fig. 1) which represents the field upon which the figures *a* and *b* are playing, and said posts *g*, *g'* are stepped into the bottom *i* (Fig. 1) so as to revolve freely therein but so as not to escape or rise therefrom. The figures *a* and *b* are so mounted upon the posts *g*, *g'* as to be free to turn with said posts, the feet of the figures *a* and *b* being clear of the top or platform *h*.

In the drawing, *j* and *j'* represent drums or spools fixed to the posts *g*, *g'*, and *k* and *k'* represent springs of metal or rubber in tension, one end of each of which being wrapped respectively about the drums *j*, *j'* in the directions shown and fixed thereto respectively by the pins *m* and *m'*, the other ends of each of said springs *k*, *k'* being fixed respectively to the posts *l* and *l'*, which posts are fixed into the platform *h* and the bottom *i*. Also, *n* and *n'* represent springs or fine wires, one end of each of which being wrapped respectively around the drums or spools *j*, *j'* in the directions shown and fixed thereto respectively by the pins *o* and *o'*, the other ends of each of said strings *n*, *n'* being wrapped respectively around the drums or spools *p* and *p'* in the directions shown and fixed thereto respectively by the pins *q* and *q'*. The drums or spools *p*, *p'* are devised with arms or projections *r* and *r'* which arms in turn bear or rest respectively against the pins *s* and *s'* which pins are fixed into the bottom *i*. The drums or spools *p*, *p'* are fixed respectively to the posts *t*, *t'* which posts are stepped into the top *h* and the bottom *i* so as to revolve freely therein. Further, *u* represents a drum or spool fixed to a post *v* which post moves freely through the top or platform *h* and

is stepped into the bottom *i* so as to turn freely therein but so as not to escape or rise from the same. The post *v* is extended to and bent at the point *w* (Fig. 1) so as to form a handle or arm *x* which handle has a knob *y* at the end thereof. The drum or spool *u* is devised with arms or projections *z* and *z'*. The arm *z'* is at such a height that it will pass over the arm *r* and will 10 strike or meet the arm *r'*, and the arm *z* is at such a height that it will pass under the arm *r'* and strike or meet the arm *r*, when the drum or spool *u* is turned or revolved by the handle *x* and the knob *y* in 15 the direction shown by the arrow *A*. The arms *z* and *z'* are placed upon the drum or spool *u* at an angle with each other, therefore, when the drum or spool *u* is revolved in the direction shown by the arrow 20 *A* the arm *z* strikes or meets the arm *r* a certain fixed time before the arm *z'* strikes or meets the arm *r'*.

The operation of the toy is as follows. When no force or pressure is used against 25 the arms *r*, *r'* to move them in the directions shown respectively by the arrows *E* and *E'*, the springs *k*, *k'* by pulling respectively upon the sides of the drums or spools *j*, *j'* in the directions shown respectively by the 30 arrows *B* and *B'*, have brought the arm *c* of the figure *a* and the bat *f* of the figure *b* into the position shown respectively at *c'* and *f'* (Fig. 2). This motion of the drums or spools *j*, *j'* has also drawn respectively 35 the strings *n*, *n'* in the directions shown respectively by the arrows *C* and *C'*, and said strings *n*, *n'* being wound respectively about the drums or spools *p*, *p'* in the direction shown have also turned said drums or spools 40 *p*, *p'* in the directions shown respectively by the arrows *D* and *D'* and the arms *r*, *r'* have been moved respectively against the pins *s* and *s'*, and the said pins *s* and *s'* being fixed, prevent further motion of any 45 of the parts of the device affected toward the directions shown respectively by the arrows *B*, *B'*, *C*, *C'*, *D*, *D'*, and consequently the various parts of the device affected by the springs *k*, *k'* are at rest. 50 To set the toy in motion the knob *y* is taken hold of by hand and turned in the direction shown by the arrow *A*, the arm *z* then comes in contact with the arm *r* and moves the said arm in the direction shown 55 by the arrow *E* and consequently the drum or spool *p* in the direction shown by the arrow *F* and the string *n* in the direction shown by the arrow *G* and the drum or spool *j* in the direction shown by the arrow *H* and the arm *c* of the figure *a* into the position shown approximately at *c'* (Fig. 2). Also, the arm *z'* comes in contact with the arm *r'* shortly after the arm *z* strikes the arm *r* and moves it in the direction shown 60 65 by the arrow *E'* and consequently the drum

or spool *p'*, the string *n'*, the drum or spool *j'*, are moved in the directions shown respectively by the arrows *F'*, *G'* and *H'* and consequently the bat *f* is brought into the position shown approximately at *f'* (Fig. 2). 70 When this part of the operation is being performed the springs *k* and *k'* are being stretched in the directions shown respectively by the arrows *P* and *P'* and are consequently in higher tension than when the device was 75 at rest. When the revolution of the drum or spool *u* is continued, the end of the arm *z* passes the end of the arm *r* and the spring *k* pulls the drum or spool *j* operating the figure *a* quickly in the direction shown by the 80 arrows *B*, *I*, *C* and *D*, and the arm *c* of the figure *a* in the direction shown by the arrow *J*, the motion in this direction being suddenly stopped by the arm *r* meeting the pin *s*. The sudden stopping of the arm *c* 85 of the figure *a* sends the ball *e* out of the recess *d* in the direction of the figure *b*. After the arm *z* has passed the arm *r* and the action above described has taken place, and at a time determined by the angle with 90 each other of *z* and *z'*, the arm *z'* passes the arm *r'* and the same motion as above described is given to the device operating the figure *b*, the motion being in the directions shown by the arrows *B'*, *I'*, *C'* and *D'* of 95 the drums or spools *p'* and *j'* and the string *n'*, all operating by the power of the spring *k'* pulling in the direction shown by the arrow *B'*. Consequently the bat *f* of the figure *b* is brought smartly in the direction shown by the arrow *J'* at exactly the right time to meet the ball *e* projected from the figure *a* and the motion in the direction shown is then stopped by the arm *r'* meeting the pin *s'*. The angle between the arms *z* 100 and *z'* is devised so as to allow just enough time to elapse after the motion has been imparted that projects the ball *e* from the figure *a* to permit of the passage of the ball *e* over the distance between the figures *a* and *b* before the motion is imparted to the bat *f* of the figure *b* so that said bat will meet the ball *e*. The operation can be continued indefinitely by replacing the ball in the recess *d* and again turning the handle *x* by the 105 knob *y*.

What I claim as my invention and desire to secure by Letters Patent, is,—

1. The combination of a base adapted to support two movable devices, one adapted 120 as described to hold a ball and the other to hold a bat, said two devices separated by an appreciable distance, and adapted as described to turn on their supports, means substantially as set forth in the form of drums, cords and a rotating arm for turning said supports, and provided with limited engaging devices adapted as described to disengage from the actuating means at different predetermined intervals, timed as set forth, 125 130

the interval being proportioned to the distance between the figures, and means for reversing the said holding devices.

2. The combination of a base adapted to support two movable devices, one adapted as described to hold a ball and the other to hold a bat, said two devices separated by an appreciable distance, and adapted as described to turn on their supports, the height of the ball holding device being adjusted as set forth whereby the bat is adapted to meet a ball projected from the ball holding device, means substantially as set forth for turning said supports, and provided with limited engaging devices adapted as described to disengage from the actuating means at different predetermined intervals, timed as set forth, the interval being proportioned to the distance between the figures, and means for reversing the said holding devices.

3. The combination of a base adapted to support two movable devices, one adapted as described to hold a ball and the other to hold

a bat, said two devices separated by an appreciable distance, and adapted as described to turn on their supports, means substantially as set forth for turning said supports and consisting of drums, cords passing about them and to the oscillatory figures, engaging arms projecting toward each other, a rotary tappet provided with crank and engaging arms adapted as set forth to engage the arms of the drums and set and proportioned as set forth whereby they will pass the ends of said drum arms sequentially, and provided with limited engaging devices adapted as described to disengage from the actuating means at different predetermined intervals, timed as set forth, the interval being proportioned to the distance between the figures, and means for reversing the said holding devices.
